UNITED STATES PATENT OFFICE.

JAMES W. RUMSEY, OF WEST BERKELEY, CALIFORNIA.

BOX-CAR-DOOR STRUCTURE.

1,236,110.

Specification of Letters Patent.

Patented Aug. 7, 1917.

Application filed December 6, 1916. Serial No. 135,459.

To all whom it may concern:

Be it known that I, JAMES W. RUMSEY, a citizen of the United States of America, and a resident of West Berkeley, county of 5 Alameda, State of California, have invented certain new and useful Improvements in Box-Car-Door Structures, of which the following is a full and clear specification.

This invention has relation to that type 10 of car-door which slides back and forth across the door-opening in the side wall of the car and the object of this invention is to provide simple means which will insure a water-tight joint or seal at the vertical edges of the door when the door is closed and which at the same time will greatly 15 increase the rigidity of the door, as more fully hereinafter set forth.

In the drawing—

20 Figure 1 is a side elevation of a portion of the side of a box-car showing my invention applied thereto; and

Fig. 2 is a horizontal section on the line 2—2 of Fig. 1.

25 In the drawing, *a* and *b* designate two hollow metal door posts which are respectively anchored to the car structure in any suitable manner. These posts are substantially similar in construction, each having 30 one of its outer vertical corners cut away to form a vertical slot in the post, the margin of this slot being formed by the front edge *c* of one of the side walls of the post and vertical edge *d* of the front wall of 35 the post.

The front vertical edge of the slidable door *e* is adapted, when the door is slid to closed position, to enter the cut-away corner 40 of the post *a* and have a substantially tight bearing on the inner face of the front wall of the post and the outer edge *c* of the side wall of the post. Fastened on the front edge of the door is an angle metal member *f*, one of whose flanges fits against the inner 45 face of the door and the other of whose flanges fits against the vertical edge of the door, this angle member being secured to the door by a series of bolts *g*. The outer face of the door along its front edge is rabbeted, and in this rabbet is fastened, by 50 means of the aforesaid bolts *g*, a vertical metal bar *h* against which the edge *d* of the front wall abuts when the door is closed. It 55 will be observed that in the act of closing the door the front edge of the angle member will pass behind the vertical edge *d* of the

post and tend to cam the door inwardly, thus pressing the inner face of the angle member against the vertical edge *c* of the side wall of the post, the movement of the door being arrested, as heretofore set forth, by the edge *d* coming in contact with the bar or strip *h*. It will be observed that this structure provides not only a rigid door post structure, but also provides for sealing the 65 front edge of the door against ingress of moisture. This structure also tends to materially stiffen the door along its front edge.

The rear edge of the door is likewise 70 provided with a metallic member which is adapted to enter the cut-away corner of the post and not only cam the door inwardly toward the body of the car, but also seal the rear edge of the door against the entrance of moisture, etc. In the present instance, 75 this metallic member consists of an angle plate *i* which is fastened to the rear edge of the door and extends along the inner face of the door, the inner member of this angle plate being set away from the inner face of the door by means of a filler strip *j* fastened to the inner face of the door. In closing the door, the inner plate of the angle member passes behind the front wall of the post and is cammed inwardly far enough to cause it 80 to bear against the vertical edge *c* of the side wall of the post, thus sealing the rear edge of the door. The filler strip *j* may have an extension *k* which may bear against the front face of the post to assist in holding 85 the door against vibration as it is closed. To further hold the door against vibration when it is closed, I may bolt the filler strip *j* inside of the post *b* in such position that its 90 inner plate of the angle iron when the door is closed and tend to press the same against the inner face of the outer wall of the post.

Having thus described my invention, what I claim is:

1. In a door structure for box-cars, two hollow metal door posts each having one of its outer corners cut away to form a vertical slot in the post, and a sliding door having a metal member at its front edge and 105 also a metal member at its rear edge, these members being adapted to enter said slots when the door is closed and have rigid contact with the walls of the posts.

2. In a door structure for box-cars, two 110 hollow metal posts each having one of its front corners cut away to form a vertical

opening in the post, one margin of this opening being formed by the vertical edge of one of the side walls of the post and the other margin being formed by the vertical edge of one of the front walls of the post, and a sliding door provided with a metal angle plate at each vertical edge of the door, these angle plates being so positioned on the door as to enter the respective openings in the post when the door is closed and make rigid contact with the post walls along the margin of the opening, the front wall of the post serving to cam the angle member inwardly toward the body of the door and press it in rigid contact with the side wall of the post.

3. In a door structure for railway cars, a hollow post having a vertical opening along one of its outer corners, the margin of this opening being formed by a vertical edge of one of the side walls of the post and by the vertical edge of one of the front walls, and a sliding door provided with an angle

iron extending along the front edge of the door and along its inner face so as to adapt it to make contact with the aforesaid margin 25 of the opening when the door is closed.

4. In a door structure for railway cars, a hollow post having a vertical opening along one of its outer corners, the margin of this opening being formed by a vertical edge of 30 one of the side walls of the post and by the vertical edge of one of the front walls, and a sliding door provided with an angle iron extending along the front edge of the door and along its inner face so as to adapt 35 it to make contact with the aforesaid margin of the opening when the door is closed, the front face of the door being rabbeted along its front edge and a vertical abutment bar or plate being fastened in said rabbet at a 40 distance back from the front edge of the door, for the purpose set forth.

In testimony whereof I hereunto affix my signature.

JAMES W. RUMSEY.
